UNITED STATES PATENT OFFICE

2,190,871

WATER HEATER

Frank Garvin, Pittsburgh, Pa.

Application March 2, 1938, Serial No. 193,461

2 Claims. (Cl. 122—23)

This invention relates to liquid heaters, particularly water heaters, and one of its main objects is to provide a heater having a high degree of efficiency of heat transfer from a burning gas to a liquid.

Another object of the invention is to provide a water heater which is of an uncomplicated, inexpensive construction, which has a long life, and requires only a minimum amount of maintenance work thereon.

Other objects will become apparent when the following detailed description is read in conjunction with the accompanying drawing, in which Fig. 1 is an elevation, partly in section, of the preferred embodiment of the invention, showing it connected to a storage tank; Fig. 2 is an enlarged longitudinal section taken on line II—II of Fig. 1; Fig. 3 is a transverse section on line III—III of Fig. 2; and Fig. 4 is a perspective view of the burner block of the heater shown in Figs. 2 and 3.

The liquid heater constructed according to this invention ordinarily comprises a metallic block which is provided with a gas chamber therein, so that the block serves as a gas burner. Numerous small ducts are formed in the block and they extend radially of the block from the gas chamber to the periphery of the block to lead gas to the atmosphere, where it burns on the surface of the block, surrounding it with a sheet of flame that heats the block to a high temperature. A bore relatively small in comparison with the cross sectional area of the block forms a water chamber extending longitudinally through the burner block. This is adapted to expose water to the heat contained in the block, and the comparatively small volume of water exposed to the relatively large mass of metal of the metallic burner greatly increases the efficiency of heat transfer to the water. Also, the small volume of water exposed to absorb heat from the burner block at any given instant, gives a rapid increase in its temperature.

A tubular extension is carried by the top of the burner block and is adapted to expose a small volume of water therein to the heated gases rising from the burner block. This increases the exposure of the water to heat from the burner before flowing from the heater.

Referring now to the drawing, a storage tank 1 is shown mounted in a vertical position on a suitable base 2. A cylindrical, vertically positioned, metallic burner block 3 is mounted adjacent the tank 1 and has an eccentrically bored longitudinal gas chamber 4 formed therein.

While any suitable metal may be used to form the block 3, it preferably is made from copper, because that metal is an excellent heat conductor, as well as non-corrosive. The gas chamber 4 extends only through a part of the length of the block 3, and connects with a plurality of radially bored ducts 5, which are formed in the block and which extend from the gas chamber to the periphery of the block. Preferably the axis of the block 3 is included in the gas chamber 4, but the gas chamber is positioned eccentric with relation thereto. The ducts 5 normally are positioned in a series of spaced planes, as seen in Fig. 1, and may be radially directed relative to the block 3 to distribute them equally over the block's surface and thereby permit gas to burn immediately adjacent all surfaces of the block, and the flame to be uniformly distributed thereover. The exposed ends of the ducts 5 are flared, or reamed, as shown, so as to hold the flame close to the block. A plug 4a is removably secured in the upper end of the block 3 to close the gas chamber 4 and seal the gas therein.

A longitudinally bored water chamber 6 extends through the block 3, positioned so that it does not connect with any of the ducts 5. Necessarily, any water in the chamber 6 contacts the block 3, through its length and readily absorbs heat therefrom. This action is expedited due to the small amount of water present in the block at any given instant. In the embodiment of the invention shown in the drawings, the ratio of the volume of metal of the block to the volume of water in the block is roughly 20 to 1 and, while I do not wish to be limited thereto, this ratio has given excellent results. Figs. 2 and 4 show the relatively small volume of the water chamber 6 in relation to the large volume of metal forming the block 3, and this is a primary feature of the invention and differentiates the burner from all burners now known to me. Fig. 2 also shows the superposed casing formed by extension member 12, having annular outer walls 12b and inner walls 12c. The annular chamber so formed is connected with the bore 6 in the burner block to permit circulation of water therebetween. It will be seen that this superposed casing forms a thin annular water chamber of small volumetric content and comparatively large surface exposure of the water therein to heat conducted through the thin outer wall 12b of the casing.

To provide the block 3 with gas, a pipe 7 extends from a source of gas supply, not shown, to a suitable valve 8 which is positioned adjacent

the block 3. The valve 8 controls the flow of gases to the block and is connected to the gas chamber 4 by an aerator 9. The aerator 9 is of standard construction, having holes 10 formed therein which are provided with adjustable covers 11 to vary the amount of air to be mixed with the gas flowing through the aerator. Thus a proper combustible mixture can be made prior to introducing the gas into the block. After the prepared mixture of gas reaches the gas chamber 4, entering through lateral bore 19, it can flow therefrom only through the ducts 5. It is then burned immediately adjacent and surrounding the surface of the block. A gas diffuser, or spreader, may be placed in the gas chamber adjacent the bore 19, if desired.

The block 3 is normally positioned with its axis extending vertically, for this permits the hot gases produced at the lower end of the block to flow along its surface as they rise. Heat is absorbed by the block from the flame surrounding it. The burning gases function to heat the block 3 to a higher temperature. The relatively large volume of the block facilitates the transfer of heat to the relatively small volume of liquid contained in the water chamber 6.

A tubular extension member 12 is secured to the top of the burner block by any suitable means, such as a threaded union 12a, and it is provided with a chamber 13 intermediate its inner and outer walls, as shown in Fig. 2. A tubular member 12b forms the outer wall of the tubular extension member 12 and is secured to a tubular member 12c forming the inner wall of the extension member by a threaded sleeve 12d. The tubular extension member connects with the upper end of the water chamber 6 and is constructed and arranged to receive water in the chamber 13 whereby the water is exposed to the hot gases rising upwardly from the burner block 3. This provides additional opportunity for heat transfer to the water prior to its removal from the heater. A baffle plate 14 having a plurality of holes therein is preferably formed integral with the tubular member 12b to divert water flowing from bore 6 into the heating chamber 13. Washers 22 and 23 are positioned at the connection between the tubular members 12b and 12c and the joint between the tubular extension member 12 and the block 3, as shown.

A pipe 15 is secured to the upper end of the tubular extension member 12 and extends to the upper portion of the storage tank 1. This permits the water heated in the burner block to rise and flow therefrom to the upper portion of the storage tank. Water circulates through the tank and back to the burner by pipe 18, in well known manner. The pipe 18 is connected to the block 3 by a coupling member 20 which provides

a preheating chamber 21 at the bottom of the block. This permits water to contact the bottom of the block and receive heat therefrom prior to its entrance into the block. A washer 24 should be placed between the block 3 and the coupling member to provide a water-tight joint.

A suitable jacket 16 is positioned around, and encloses the block 3 and exhausts the gases produced by combustion through a flue 17.

Practice of the invention increases the efficiency of heat transfer between the burning gas and the liquid to be heated for the large volume of metal in the burner relative to the amount of liquid therein produces this highly desirable result. It will be seen that the shape of the burner, or heater, block may vary widely without departing from the inventive concept.

According to the provisions of the patent statutes, I have explained the principle and mode of operation of my invention and have illustrated and described what I now consider to represent its best embodiment. However, I desire to have it understood that, within the scope of the appended claims, the invention may be practiced otherwise than as specifically illustrated and described.

I claim:

1. A water heater adapted for use with a storage tank, comprising a vertically positioned metallic block having a gas chamber formed therein and a plurality of bores leading from the chamber to the periphery of the block, said block also having a relatively small water-receiving chamber extending longitudinally therethrough, means for leading combustible gas to said gas chamber, and a tubular extension member secured to the top of said block and connected to said water-receiving chamber, said tubular extension member being constructed and arranged to expose water to gases of combustion rising upwardly from said block.

2. A water heater comprising a metallic block having a gas chamber formed therein, a plurality of bores formed in the block and extending from said chamber to the periphery of the block, a relatively small water chamber extending longitudinally through the block, and means secured to the top of said block and adapted to receive water from said water chamber and expose it to heated gases rising from said block comprising a superposed casing mounted on the heater block, the interior of said casing being connected to the water chamber in the heater block, the casing comprising inner and outer walls so spaced as to provide an annular water-containing space of small volume and relatively large surface exposure to external heat.

FRANK GARVIN.
